UNITED STATES PATENT OFFICE

CLAUDE C. RITTER, OF BUCKEYE, ARIZONA

DESIGN FOR A COMBINED MIRROR AND FRAME

Application filed October 12, 1931. Serial No. 41,364. Term of patent 3½ years.

To all whom it may concern:

Be it known that I, CLAUDE C. RITTER, a citizen of the United States, residing in Buckeye, in the county of Maricopa and State of Arizona, have invented a new, original, and ornamental Design for a Combined Mirror and Frame, of which the following is a specification, reference being had to the accompanying drawing, forming part thereof, in which the figure is a perspective view of the combined mirror and frame.

I claim:

The ornamental design for a combined mirror and frame, as shown.

Signed at Buckeye, in the county of Maricopa and State of Arizona, this 8th day of September, 1931.

CLAUDE C. RITTER,
